(57) **CLAIM**

We claim the ornamental design for a golf putter face, as shown and described.

DESCRIPTION

FIG. 1 is a front elevational view of a golf putter face showing one embodiment of our new design; and,

FIG. 2 is a front elevational view of a golf putter face showing another embodiment of our new design.

The broken line showing of other portions of a golf putter head is for illustrative purposes only and forms no part of the claimed design.
